WIRE STRETCHING AND TWISTING DEVICE

Garnet C. Johnson, Pasadena, Calif.

Application December 6, 1940, Serial No. 368,794

8 Claims. (Cl. 140—123.5)

This invention relates to wire stretching and twisting devices.

The general object of my invention is to provide an improved portable, readily operable means, enabling two ends of a wire, such as might be used in concrete forms or about bales or bundles and in other places, to be readily stretched and twisted so that the wire will remain in position.

A further object of my invention is to provide a wire tightening and twisting device, including a pair of pivoted arms having wire engaging members thereon and operable to tighten and twist the ends of a wire.

Another object of the invention is to provide a wire tightening and twisting device, including a pair of arms, each having an arcuate cam member thereon provided with a wire engaging portion for engaging an end of a wire.

A further object of the invention is to provide a wire tightening and twisting device, including a pair of pivoted arms with each arm having a curved plate thereon and each curved plate having a wire engaging post thereon.

Other objects and advantages of my invention will be apparent from the following description taken in connection with the accompanying drawings wherein:

Fig. 1 is a top plan view of a wire stretching and twisting device embodying the features of my invention;

Fig. 2 is a side elevation showing the device;

Fig. 3 is a front view of the device;

Fig. 4 is a section taken on line 4—4, Fig. 1;

Fig. 5 is a fragmentary top plan view showing the device in use and with the wire ends secured in place;

Fig. 6 shows the device after the handles are spread apart and the wire has been stretched and twisted;

Fig. 7 is a view similar to Fig. 5, showing an alternative manner of holding the wire ends;

Fig. 8 is a fragmentary top plan view, showing a modification, and

Fig. 9 is a side elevation, partly in section, showing the modification.

Referring to the drawing by reference characters I have shown my invention as embodied in the wire stretching and twisting device which is indicated generally at 10. As shown the device includes a pair of arms or handles 11 which are suitably pivoted together by a fastening member such as a threaded button 12 which passes through holes 13 at the forward end of the arms. Other holes 14 and 15 in the arms provide for adjustment of the pivoted mounting.

The arms at their forward ends (Fig. 2) are parallel and adjacent as at 16 while at the rear ends at 17 they preferably diverge to provide a space 18 to receive the fingers of the operator.

At the forward end each of the arms 11 is provided with an arcuate engaging member 19 which is welded to the end 20 of the associated arm. Each engaging member is shown as provided with a reinforcing strip 21 which is welded thereto as at 22. Each reinforcing strip is also welded as at 23 to the adjacent arm.

The opposed ends of the adjacent engaging members as shown in Fig. 3 are provided with notches 24 and with tongues 25 which project beyond the notches.

Each engaging member 19 is further provided with a wire engaging post 26 and with a wire securing post 27. These posts 26 and 27 are suitably welded as at 28 and 29 to the engaging members. The post 26 is preferably provided with a wire receiving slot 30.

In the use of my device the handle members 11 are moved from the position shown in Fig. 1 to the position shown in Fig. 5. The ends 31 and 32 of a wire 33, arranged loosely about form members or other members 34, are inserted in the notches 24. The ends 31 and 32 are then twisted about the tongues 25 as indicated at 35. The engaging members 19 are positioned against one of the form or other members while this is being done.

The handles 11 are then brought together to the position shown in Fig. 6 and the handles are then rotated thus twisting the wire as at 36 to secure the ends together. The handles 11 may then be slightly spread apart permitting the tongues 25 to pass from the twist 36 in the wire ends so that the handles may be readily removed.

When the posts 26 and 27 are employed the wire ends 37 as shown in Fig. 7 run through the notches 24 to the post 26 into the notches 30 and then to the post 27 about which they may be bent as at 38. The handles 11 are then rotated to form a lock twist 39 after which the device may be removed.

In Figs. 8 and 9, I show a modification of my invention. In this modification, a pair of handle members 11' are pivoted together as at 12'. Each handle has a cylindrical engaging member 19' secured thereto with the end of the handle welded at 40 to the inner periphery of the member 19', and with the handle passing through a slot 41 in the member 19' and welded in the slot as at 42. The members 19' are the same size and bear upon each other as shown in Fig. 9, and each member has a notch 43 in its periphery with a tongue 44 bent up from the notch. The notches are V shaped, as shown, so that the ends of wires may be passed through the notches and twisted around the tongues 44. The front of each member 19' is knurled as at 45 to provide a rough, ripping surface. The operation of the modification is substantially the same as that previously de-

scribed and a further description thereof is believed unnecessary.

From the foregoing description it will be apparent that I have invented a novel wire stretching and wire twisting device which can be economically manufactured and which is highly efficient for its intended purpose.

Having thus described my invention I claim:

1. In a wire stretching and twisting device, a pair of arms, means to pivotally connect said arms, the arms including adjacent portions at the forward ends and spaced portions at the rear ends thereof, an arcuate engaging member arranged transverse to and secured upon the forward end of each arm, the engaging members being disposed in side by side relation, one of said engaging members having a notch therein at one end and having a tongue projecting beyond the notch and the other engaging member at the end remote from said one end having a second notch therein and having a second tongue projecting beyond the second notch.

2. In a wire stretching and twisting device, a pair of arms, means to pivotally connect said arms, the arms including adjacent portions at the forward ends and spaced portions at the rear ends thereof, an arcuate engaging member arranged transverse to and secured upon the forward end of each arm, the engaging members being disposed in side by side relation, one of said engaging members having a notch therein at one end and the other engaging member at the end remote from said one end having a notch therein, said engaging member adjacent the notch and thereof having a wire engaging post projecting rearwardly therefrom, each wire engaging post having a slot in the end thereof remote from the engaging member.

3. In a wire stretching and twisting device, a pair of arms, means to pivotally connect said arms, the arms including adjacent portions at the forward ends and spaced portions at the rear ends thereof, an arcuate engaging member arranged transverse to and secured upon the forward end of each arm, the engaging members being arranged in side by side relation, each engaging member having an arcuate reinforcing strip secured to the rear thereof, each reinforcing strip being secured to the adjacent arm, one of said engaging members having a notch therein at one end and having a tongue projecting beyond the notch and the other engaging member at the end remote from said one end having a notch therein and having a tongue projecting beyond the notch.

4. In a wire stretching and twisting device, a pair of arms, means to pivotally connect said arms, the arms including adjacent portions at the forward ends and spaced portions at the rear ends thereof, an arcuate engaging member arranged transverse to and secured upon the forward end of each arm, the engaging members being disposed in side by side relation, one of said engaging members having a notch therein at one end and having a tongue projecting beyond the notch and the other engaging member at the end remote from said one end having a notch therein and having a tongue projecting beyond the notch, said engaging member adjacent the notch end thereof having a wire engaging post projecting rearwardly therefrom, each wire engaging post having a slot in the end thereof remote from the engaging member.

5. In a wire stretching and twisting device, a pair of arms, means to pivotally connect said

arms, the arms including adjacent portions at the forward ends and spaced portions at the rear ends thereof, an arcuate engaging member arranged transverse to and secured upon the forward end of each arm, the engaging members being arranged in side by side relation, each engaging member having an arcuate reinforcing strip secured to the rear thereof, each reinforcing strip being secured to the adjacent arm, one of said engaging members having a notch therein at one end and the other engaging member at the end remote from said one end having a notch therein, each engaging member adjacent the notch end thereof having a wire engaging post projecting rearwardly therefrom, each wire engaging post having a slot in the end thereof remote from the associated engaging member.

6. In a wire stretching and twisting device, a pair of arms, means to pivotally connect said arms, the arms including adjacent portions at the forward ends and spaced portions at the rear ends thereof, an arcuate engaging member arranged transverse to and secured upon the forward end of each arm, the engaging members being disposed in side by side relation, one of said engaging members having a notch therein at one end and having a tongue projecting beyond the notch and the other engaging member at the end remote from said one end having a notch therein and having a tongue projecting beyond the notch, said engaging member adjacent the notch end thereof having a wire engaging post projecting rearwardly therefrom, each wire engaging post having a slot in the end thereof remote from the engaging member and each engaging member at the end thereof remote from the tongue thereon having a wire securing post thereon.

7. In a wire stretching and twisting device, a pair of arms, means to pivotally connect said arms, the arms including adjacent portions at the forward ends and spaced portions at the rear ends thereof, an arcuate engaging member arranged transverse to and secured upon the forward end of each arm, the engaging members being arranged in side by side relation, each engaging member having an arcuate reinforcing strip secured to the rear thereof, each reinforcing strip being secured to the adjacent arm, one of said engaging members having a notch therein at one end and having a tongue projecting beyond the notch and the other engaging member at the end remote from said one end having a notch therein and having a tongue projecting beyond the notch, said engaging member adjacent the notch end thereof having a wire engaging post projecting rearwardly therefrom, each wire engaging post having a slot in the end thereof remote from the associated engaging member and each engaging member at the end thereof remote from the tongue thereon having a wire securing post thereon.

8. In a wire stretching and twisting device, a pair of overlapping arms, means to pivotally connect said arms, said arms including spaced portion at the rear ends thereof, an engaging member secured upon the forward end of each arm, the engaging members being disposed one above the other in superimposed relation, each engaging member having an arcuate outer end surface adapted to be engaged by a wire, the arcuate ends being aligned, and wire anchoring means for securing a wire to each engaging member.
